UNITED STATES PATENT OFFICE.

EDWARD KRUMLAND, OF COLUMBUS, NEBRASKA.

HAULING ATTACHMENT FOR AUTOMOBILES.

1,284,712.

Specification of Letters Patent. Patented Nov. 12, 1918.

Application filed November 1, 1917. Serial No. 199,698.

To all whom it may concern:

Be it known that I, EDWARD KRUMLAND, a citizen of the United States, residing at Columbus, in the county of Platte and State of Nebraska, have invented certain new and useful Improvements in Hauling Attachments for Automobiles, and I do declare the following to be a full, clear, and exact description of the invention, such as will enable others skilled in the art to which it appertains to make and use the same.

My invention has for its object to provide a simply constructed and inexpensive, yet a highly efficient and durable device which may be placed in the tonneau of an automobile for hauling purposes, the device being so constructed that it may be compactly folded when not in use.

With the foregoing general object in view, the invention resides in the novel features of construction and unique combinations of parts to be hereinafter fully described and claimed, the descriptive matter being supplemented by the accompanying drawings which form a part of this specification and in which:

Figure 1 is a top plan view of a portion of an automobile showing the application of the invention;

Fig. 2 is a longitudinal section of the body of the machine illustrating an end elevation of the invention;

Fig. 3 is a duplicate of Fig. 2 with the exception that it illustrates the invention in longitudinal section;

Fig. 4 is a transverse section of a portion of Fig. 3 of the plane indicated by the line 4-4 thereof;

Fig. 5 is a sectional view similar to Fig. 3 but illustrating the device in folded position;

Fig. 6 is a perspective view of the invention in readiness for folding;

Fig. 7 is an end elevation of the device removed from the car; and

Figs. 8 and 9 are transverse sections on the planes of the lines 8-8 and 9-9 of Fig. 7.

In the drawings above briefly described, the numeral 1 designates a horizontal platform of a size and shape to rest upon the rear seat frame 2 of an automobile, a platform extension 3 being hinged at 4 to the front edge of said platform to extend therefrom substantially to the front seat. Legs 5 are hinged at 6 to the front edge of the

extension 3 for supporting the latter when in use, and any suitable means such as hooks 7 may be employed for holding said legs against folding until required.

Side boards 8 and 9 are permanently secured to the rear edge and to the ends of the platform 1 in any preferred manner, and another side board 10 is hinged at 11 to the front edge of the platform extension 3, while removable side boards 12 extend from the front ends of the boards 9 to the board 10, said boards 12 having cleats 13 against which said board 10 rests as shown clearly in the drawing. Hooks or the like 14 are provided for securing the front ends of the removable side boards 12 to the board 10, and for the purpose of preventing lateral shifting of said board 12, pins 15 preferably depend therefrom through openings 16 in the platform extension 3, said pins being formed on the lower ends of vertical bars or plates 17 which extend across and are secured to the boards 12. It is to be observed that these boards 12 are located in alinement with the rear doors 18 which lead into the tonneau of the machine. It will thus be seen that by removing these boards and opening the doors, the objects to be hauled may be easily placed upon the device.

When not in use, the boards 12 are removed, before the board 10 is folded rearwardly upon the platform extension 3, this extension is then folded rearwardly upon the platform 1, and the legs 5 are finally folded onto the extension. The entire device is thus compactly arranged upon the seat frame and if required the seat cushion may be used without removing the attachment, but in most cases this will not be done.

From the foregoing, taken in connection with the accompanying drawings, it will be obvious that although my invention is of extremely simple nature it will be highly efficient and durable for the purpose intended, particular emphasis being placed upon the fact that the device is compactly foldable and is provided with detachable side boards 12 in line with the rear doors, to permit easy loading.

Since probably the best results are obtained from the several specific details shown and described, they will preferably be employed, but I wish it understood that within the scope of the invention as claimed, numerous minor changes may well be made.

Also, the device may be constructed in numerous sizes and designs for application to different makes of machines.

I claim:

- 5 A hauling attachment for automobiles comprising a rear platform section elongated transversely of the car and adapted to rest on the rear seat, said rear section having permanently and rigidly attached rear side and end walls, a front platform section also elongated transversely of the machine and hinged to said rear section for folding thereon, means for supporting said front platform section, a front wall rising from
- 10 15 and hinged to said front section for folding thereon, a pair of removable end walls rising

from the ends of said front section and lying against the inner sides of said first named end walls, releasable means connecting the front ends of said removable end walls with the front wall of said front platform section, and rigid studs depending from said removable end walls, said front platform section having openings receiving said studs.

In testimony whereof I have hereunto set 25 my hand in the presence of two subscribing witnesses.

EDWARD KRUMLAND.
